RUBBER CURBING ASSEMBLY OR THE LIKE

Sheldon Westervelt, Oradell, N.J., assignor to Wm. C. Westervelt & Sons, Franklin Lakes, N.J., a corporation of New Jersey

Filed Jan. 31, 1969, Ser. No. 15,583

Term of patent 14 years

Int. Cl. D25—05

U.S. Cl. D60—1

FIG. 1 is a perspective view of a rubber curbing assembly, or the like, showing my new design;

FIG. 2 is an end view thereof;

FIG. 3 is a bottom view of the assembly of FIG. 1; and FIG. 4 is a longitudinal section of the curbing assembly, as indicated by the arrows 4—4, of FIG. 1.

I claim:

The ornamental design for a rubber curbing assembly or the like, substantially as shown.
